Newark Engineering Company, Hillside, N. J.,
a corporation of New Jersey

Original application August 2, 1940, Serial No.
349,850. Divided and this application January
18, 1944, Serial No. 518,699

9 Claims. (Cl. 198—103)

1

This invention relates to an improved conveyer construction for transferring, from one point to another, articles of circular cross section. The present case is a division of my pending application Serial No. 349,850, filed on August 2, 1940.

An object of the invention has been to provide an endless conveyer adapted to receive articles of circular cross-section from a coating or printing machine or the like and transfer the same, without marring the surface of the article, to a point of desired disposition. In achieving this purpose, the invention provides an endless conveyer member, preferably in the form of a chain, having a plurality of transversely extending pivot pins upon which are swivelly mounted a series of article receiving cups or buckets. The arrangement is such that the cups or buckets will be constantly maintained in a definite position, i. e. with their open tops facing upwardly and their bottoms down, as they are carried along by the movement of the conveyer member. This is accomplished automatically, by gravity, as a result of the swivelled mounting of the cups.

A special feature of the invention is the formation of the article retaining cups or buckets in such a way that articles of circular cross-section will be retained thereby with only a few spaced points thereof in engagement with surfaces of the cups. In the application of the invention to a conveyer for articles such as glass ampules, the construction is such that the ampule will be supported by the edge of its base and by a small shoulder engaging a point on the long neck of the ampule. This avoids any danger of marring any printed or decorative matter on the body of the ampule.

In the operation of typical apparatus embodying the invention, the articles, after being printed upon or coated, are dropped one by one by gravity from a carrier associated with the printer into successive buckets or cups, above mentioned, carried by the endless conveyer means. The conveyer carries the articles at a predetermined, uniform speed through a drying zone, which may suitably involve an oven or similar enclosed, drying chamber maintained at a controlled temperature. In the course of such movement, the cups will be carried along a rather circuitous path but at all times they will be maintained with their open tops facing upwardly. The arrangement is preferably such that the conveyer is advanced continuously, even though the printing or coating machine may be temporarily stopped. When the successive cups emerge from the drying zone, the printed matter or coating on the sur-

2

faces of the articles carried thereby will be sufficiently dry to prevent marring even though these surfaces are brought into engagement with each other or with other surfaces. The articles may, accordingly, then be discharged or removed from the cups, either automatically or manually, and deposited in a suitable receptacle or packed in an appropriate container.

Other objects, features and advantages of the invention will appear from a detailed description of an illustrative form of the same, which will now be given in conjunction with the accompanying drawings, in which:

Fig. 1 is an elevational view, somewhat schematic, of a printing mechanism and an associated conveyer and dryer which may embody the present invention.

Fig. 2 is a transverse section through the printer, taken along the line 2—2 of Fig. 1, and shows a portion of the conveyer associated with the printer.

Fig. 3 is an enlarged view, partly in elevation and partly in vertical section, showing an article carrier, forming part of the printer, and the associated conveyer.

Fig. 4 is a transverse sectional view taken along the line 4—4 of Fig. 3, and

Fig. 5 is a fragmentary detail showing in transverse section a modified conveyer cup.

Referring now to the drawings, the illustrative apparatus includes a printing unit which is generally designated 16 (Fig. 1). This printing unit is mounted on a pedestal 17 which encloses the power means for operating the equipment, including, in addition to the printing unit, a conveyer chain 18. The arrows shown on the conveyer chain indicate the direction of movement of the various courses. The conveyer chain carries the printed containers to and through a drying chamber 19 in which the containers are subjected to a uniform and regulated drying temperature which may be maintained in any convenient way, as by the circulation of heated air or the like, preferably under the control of thermostatic devices, not shown. After traversing a series of loops or slings within the drying chamber, the conveyer chain passes outwardly at the opposite side of the chamber and then upwardly to a delivery table or unloading station 20. Here the printed and dried containers are automatically removed by dumping from the conveyer and may be suitably packed in cartons or the like by hand or by any appropriate automatic means. From the delivery table the conveyer chain travels into the drying chamber up-

wardly along the adjacent end wall, then across the top and then downwardly along the opposite end wall through which it is passed outwardly at a point near the bottom and returned to the printing unit through its supporting pedestal. The means for driving the conveying chain from within the pedestal will be hereinafter explained.

The printing unit (Fig. 2) is carried by a main frame comprising a vertically disposed web 21 having laterally extending flanges 22 and 23 around three sides and having similar flanges 24 of greater width at its base. A cover 24a, extending from the outer edge of flange 22 to the outer edge of flange 24, may be provided to enclose the driving mechanism, which will be later described. Near the bottom of the vertical web 21 is a hollow boss 25 forming a socket to receive a reduced hub portion 26 of a boss 27 at the lower end of an auxiliary frame member 28. This auxiliary frame is adapted to rock or pivot slightly by the turning of the hub portion 26 within the boss 25. Near its upper end the auxiliary frame 28 carries an integral sleeve 29 which extends through an aperture 30 in the web 21, this aperture being of sufficient size to permit a slight rocking or pivotal movement of the auxiliary frame, as explained. Above the sleeve 29 the auxiliary frame is formed with an ear 31 having an aperture 32, slightly elongated in a circumferential direction, to receive a locking bolt 33 having screw-threaded engagement with the web 21. The bolt 33 thus provides means for clamping the auxiliary frame in any adjusted position permitted by the construction described. To effect the desired adjustment of the auxiliary frame, it is provided with a block 34, swivelled to the frame. A screw 35, threaded in the block 34, may be turned to shift the auxiliary frame about the axis of the hub 26 to the desired extent and the frame may then be clamped in its set position by the tightening of the bolt 33.

Within the sleeve 29 of the auxiliary frame there is journaled a shaft 38 (Fig. 2) to which is keyed, adjacent its righthand end, a carrier member 39 which serves to support and convey the ampoules or other articles to be printed. A clamping collar 40 may be provided to retain the carrier upon the shaft. This construction is such that the carrier may be readily removed whenever it is desired to replace it by another carrier adapted for larger or smaller articles.

The carrier is essentially a relatively broad, disc-like member having a series of recesses or pockets 41 (Fig. 3) at spaced intervals in its periphery. Adjacent each of these recesses and on both faces of the carrier there is provided a pair of discs 42 freely rotatable upon studs 43 mounted in the carrier. These discs 42 are so arranged that their peripheries extend slightly beyond the surfaces defined by the recesses 41. Accordingly, these discs serve to support the ampoules or other articles in such a way as to prevent contact of their surfaces with the surfaces defining the recesses 41. The outer periphery of the carrier is of generally cylindrical form, as indicated at 44, but in advance of each of the recesses 41 the outer surface of the carrier is inclined inwardly substantially toward the axis of the recess, as indicated at 45. This enables the carrier readily to pick up the articles, such as ampoules X, which are delivered to the machine by means of a chute 46. As the lowermost ampoule is picked up by one of the recesses 41, the next ampoule will roll along the adjacent surface 44 of the carrier and then down the inclined por-

tion 45 into the next recess which is brought opposite the chute. The chute 46 may be supplied with the articles to be printed in any suitable way, either by hand or by automatic means. It is supported by means of a bracket 47 having a split collar 48 at its lower end adapted to surround and be clamped upon the sleeve 29 of the auxiliary frame. The arrangement is preferably such that the chute 46 will be inclined slightly from front to rear (Fig. 3), i. e., downwardly toward the web 21, so as to cause the ampoules to remain by gravity toward the rear of the chute.

As best shown in Fig. 4, a disc or plate 49 is provided between the carrier and the end of the sleeve 29, this disc being secured to the sleeve by means of a bracket 50. The disc in turn carries an angle bracket 51 arranged to support a guide 52 which extends over the top of the carrier. Adjacent the lower end of the chute the guide 52 is curled upwardly, as indicated at 53 (Fig. 5), and at its opposite end 54 the guide extends adjacent to the printing station, to be later described. Another guide 55 (Figs. 2, 3 and 4) is provided below the printing station, this guide having an opening or cut-away portion 56 in the region over which rolls the printed matter on the ampoules. Preferably the connecting portions at the ends of the opening 56 are offset radially to a slight extent so as to lie outwardly of the inner surface of the guide. It will be understood that the guide 55 serves to retain the ampoules in the pockets 41 and for this reason, after the ampoules have been printed upon, it is necessary to guard against smearing of the ink. The lower guide 55 is carried by a disc 57 secured to an arm or bracket 58 carried by a stationary shaft 59 extending through the hub 26 of the auxiliary frame and the boss 25 of the main frame. By shifting the bracket 58 axially of the shaft 59, adjustment may be made for ampoules of different length. A setscrew 60 may be provided at the bottom of the bracket 58 for retaining the latter in desired position on the shaft 59. At the top of the disc 57 a laterally extending support 61 is provided. This carries an adjustable bracket 62, which may be clamped in any adjusted position by a screw 63. The inner end of bracket 62 carries a flexible spring finger 64 adapted to engage the outer ends of the ampoules to press them lightly against the disc 49 as the ampoules are carried into printing position. This insures the correct positioning of the ampoules as they are being printed.

As the ampoules with the printed impression thereon are carried beyond the lower end 65 of the guide 55, they are permitted to drop by gravity into a series of cups or buckets 66 carried by the conveyer chain 13, previously mentioned. These cups are freely supported by pins or rods 67 formed as extensions of the roller supporting pivots for the links of the conveyer chain. Just beneath the carrier 39 the conveyer passes around a sprocket wheel 68, loosely mounted upon the previously described shaft 59. A collar 69 serves to retain the sprocket in place. Each of the cups 66 is provided with a weighted bottom 70 which serves to maintain the cup in an upright position throughout its movement with the conveyer chain. To reduce to a minimum the sagging of the cups due to the cantilever effect, the weighted portion of the bottom may, if desired, be concentrated near the chain, as shown at 70a in Fig. 5. At its rear or inner end each cup is provided with a trough 71 and at its outer end

with a substantially vertical wall 72 having a shallow notch 73.

It will be understood that the conveyer chain is adapted to be driven in synchronism with the carrier 39, the arrangement being such that as an ampule is discharged from the carrier, one of the cups 66 will be directly beneath the latter to receive the ampule. Due to the construction of the cup, a portion of the long tip of the ampule will engage the depression 73 while the periphery of the bottom of the ampule will engage either the top of the pin 67 or the sloping walls of the trough portion 71 of the cup. As a result, none of the printed matter on the ampule will come in contact with any part of the cup and the danger of smearing the printed impression is eliminated.

The printing upon the ampules at the printing station is effected by means of a soft, resilient transfer roller 74, (Fig. 3) formed of rubber or any composition commonly employed in inking rolls. It is adapted to receive an impression from one or more printing members (not shown) in the manner fully disclosed in said parent application. Roller 74 is driven at an appropriate speed in synchronism with the carrier 39. In dealing with relatively small ampules, of a diameter of less than one-half inch, the carrier may be operated continuously and the printing operation performed while the ampule is being advanced by the carrier. The peripheral speed of the roller 74 will be considerably faster than that of the carrier so that the ampule will be rotated and receive an impression at the printing station. When larger ampules or other containers are dealt with, it is preferable to operate the carrier intermittently, it being held stationary during the printing operation. However, regardless of whether the carrier is operated intermittently or continuously, the conveyer carrying the cups 66 may be advanced continuously in synchronized relation.

For the purpose of driving the printing devices and the conveyer chain 18, a motor (not shown) may be provided within the pedestal portion 17 of the printer. This may be connected by a chain 122 (Fig. 2) with a sprocket 123 secured to a driving shaft 124 for the printer. It may also be connected by suitable chains and sprockets (not shown) with a shaft 140 (Fig. 1) which carries a sprocket 141 by means of which the conveyer chain 18 is continuously advanced. The arrangement is preferably such that the conveyer chain will be advanced so long as the driving motor is in operation, regardless of whether or not the printer is in operation. This insures subjecting all printed articles to the same drying conditions. The connections from the motor to the printer and conveyer are such that the cups 66 will be advanced at the same speed as the pockets 41 in the carrier, whenever the printer is operating, and the clutch for throwing the printer in and out of operation is such as to keep the carrier and conveyer properly synchronized. For further details as to the driving means, reference may be had to said parent application.

In the operation of the machine, the ampules X may be supplied either automatically or by hand to the chute 46. When the printer is in operation, the ampules will be delivered one by one to the pockets of the carrier 39 and brought first to the printing station, to receive an impression from the roller 74, and then to the end 65 of the lower guide 55 from which they drop into the cups or buckets 66 which are successively

brought into position to receive the ampules as they are released by the guide. The conveyer chain 18 carries the cups with their ampules along a circuitous path leading into, through and out of the dryer 19. Due to their weighted bottoms, the cups always remain with their open tops facing upwardly until they reach the delivery or packing station 20 where they may be tilted to discharge the ampules or the latter may be lifted from the cups.

While an illustrative machine embodying the various features of the present invention and certain modifications have been disclosed in considerable detail, it will be understood that numerous other changes may be made in the construction and arrangement of the various parts without departing from the general principles and scope of the invention. The terms and expressions used herein have been used as terms of description and not of limitation.

I claim:

1. In apparatus of the class described an endless conveyer comprising a chain, a plurality of pins projecting from said chain, and cups freely mounted on said pins, said cups having weighted bottoms to hold the same upright by gravity, each cup having a trough-like portion adapted to receive the base of a container and a notched end-plate adapted to support the container adjacent its opposite end, the arrangement being such that the container is held with the portion of its surface between the base and opposite end free and clear of the cup.

2. In apparatus of the class described an endless conveyer comprising a chain, a plurality of pins projecting from said chain, and cups freely mounted on said pins, said cups having weighted portions in their bottoms adjacent the chain to hold the same upright by gravity, each cup having a trough-like portion adapted to receive the base of a container and a notched end-plate adapted to support the container adjacent its opposite end, the arrangement being such that the container is held with the portion of its surface between the base and opposite end free and clear of the cup.

3. In apparatus of the class described an endless conveyer comprising a chain, means for advancing said chain, a plurality of article receiving buckets swivelly mounted on said chain, each bucket having a bottom, side and end walls and an open top, weight means for holding each bucket with its open top facing upwardly throughout the movement of said chain, and each bucket having article supporting surfaces adapted to engage articles of circular cross-section at only a pair of longitudinally spaced points, said surfaces being arranged to retain said articles in definite endwise position with respect to the pocket.

4. In apparatus of the class described an endless conveyer comprising a chain, means for advancing said chain, a plurality of article receiving buckets swivelly mounted on said chain, each bucket having a bottom, side and end walls and an open top, weight means for holding each bucket with its open top facing upwardly throughout the movement of said chain, and each bucket having article supporting surfaces adapted to engage articles of circular cross-section and of different dimensions at only a pair of longitudinally spaced points, said surfaces being arranged to retain said articles in definite endwise position with respect to the pocket.

5. In apparatus of the class described an end-

less conveyer comprising a chain, means for advancing said chain, a plurality of article receiving buckets swivelly mounted on said chain, each bucket having a bottom, side and end walls and an open top, weight means for holding each bucket with its open top facing upwardly throughout the movement of said chain, and each bucket having article supporting surfaces adapted to engage articles of circular cross-section only at points adjacent the ends of said articles, said surfaces being arranged to retain said articles in definite endwise position with respect to the pocket.

6. In apparatus of the class described an endless conveyer comprising a chain, means for advancing said chain along a circuitous path, a plurality of article receiving receptacles swivelly mounted on said chain, each receptacle being held with its top and bottom in predetermined relation throughout its movement, and means for depositing an article by gravity in each of said receptacles as it passes a predetermined point, said receptacles being so constructed and arranged that said articles are received, engaged and supported by surfaces on the receptacles at only a plurality of widely separated points as they are deposited in and conveyed by the receptacles, said surfaces being arranged to retain said articles in definite endwise position with respect to the receptacles.

7. In apparatus of the class described an endless conveyer comprising a chain, means for advancing said chain along a circuitous path, a plurality of article receiving receptacles swivelly mounted on said chain, each receptacle being held with its top and bottom in predetermined relation throughout its movement, and means for depositing an article by gravity in each of said receptacles as it passes a predetermined point, said article depositing means and said receptacles having surfaces thereon so constructed and arranged that said articles are engaged and sup-

ported thereby at only a plurality of widely separated points as they are brought to, deposited in and conveyed by the receptacles, said surfaces on said receptacles being arranged to retain said articles in definite endwise position with respect to the receptacles.

8. In apparatus of the class described an endless conveyer comprising a chain, means for advancing said chain along a circuitous path, a plurality of article receiving receptacles swivelly mounted on said chain, each receptacle being held with its top and bottom in predetermined relation throughout its movement, and means for depositing an article by gravity in each of said receptacles as it passes a predetermined point, said receptacles having surfaces thereon so constructed and arranged that said articles are engaged and supported thereby only at points adjacent their ends as they are deposited in and conveyed by the receptacles, said surfaces being arranged to retain said articles in definite endwise position with respect to the receptacles.

9. In apparatus of the class described a plurality of article conveying means, means for driving said conveying means in synchronism, one of said conveying means being arranged to deliver articles conveyed thereby by gravity to the other of said conveying means, said one of said conveying means being arranged to support said articles during at least a portion of the travel thereof with a substantial part of the surface of said articles extending completely around the same free and clear of any engagement, and a plurality of swivelly mounted receptacles on said other conveying means arranged to receive and convey said articles, said receptacles having surfaces adapted to receive and retain said articles without engagement of said part of the surface thereof, said surfaces on the receptacles being arranged to retain said articles in definite endwise position with respect to the receptacles.

JOHN H. FRIDÉN.
